UNITED STATES PATENT OFFICE.

AUSTIN VICKERS, OF ASBURY PARK, NEW JERSEY.

UNDERGARMENT.

1,104,534.

Specification of Letters Patent.

Patented July 21, 1914.

Application filed March 19, 1913. Serial No. 755,465.

To all whom it may concern:

Be it known that I, AUSTIN VICKERS, a subject of the King of Great Britain, residing at Asbury Park, in the county of Monmouth and State of New Jersey, have invented certain new and useful Improvements in Undergarments; and I do hereby declare the following to be a full, clear, and exact description of the invention, such as will enable others skilled in the art to which it appertains to make and use the same.

This invention relates to new and useful improvements in undergarments, and more particularly to that class of garments known as drawers.

The object of my invention is to provide a garment wherein the opening will remain closed at all times except when the wearer desires it to be opened.

Another object of my invention is to provide a garment which will fit closely to the hips and limbs at all times, an advantage which is so desirous at the present time, inasmuch as the styles require garments which fit closely to the person of the wearer.

A further object of my invention is to provide a garment wherein the overlying portions will lie smooth at all times and will not cause undue wrinkles, etc., which would present an unsightly appearance.

A still further object of my invention is to provide a garment of the above type to which an apron or shield is adapted to be attached during certain periods, the apron being of a waterproof fabric, which will protect the outer garments, etc.

With the above and other objects in view, I will now proceed to describe my invention in the following specification and accompanying drawings, in which—

Figure 1 is a rear view of my improved undergarment; Fig. 2 is a front view of the same; Fig. 3 is a rear view of the undergarment with the apron attached thereto; and Fig. 4 is a longitudinal sectional view taken on line 4—4 of Fig. 3.

Referring to the drawings by characters of reference, 5 indicates a limb receiving portion adapted to coöperate with the limb receiving portion 6. An enlarged flap 7 is formed integral with the limb receiving portion 5 and is adapted to overlie a similar portion 8 formed on the limb receiving portion 6. The front of the garment is preferably stitched, as shown at 9, and is provided with flaps, as previously referred to, as 7

and 8. These limb receiving portions are preferably tubular in shape and are stitched at their inner extremity, so that they completely encircle the limb adjacent their lower end. Suitable slits are provided, which are adapted to close automatically when the garment is adjusted in place.

To the rear flap 8 I preferably secure buttons 10, which are adapted to coöperate with button-holes 11, whereby the garment is permitted to be removed. These buttons are three in number and one of said buttons is secured to one of the flaps immediately adjacent its end. Another of the buttons is placed substantially in the center of the garment and the third button is secured to the waist band at a point substantially the same distance from the center button as the first mentioned button. The button holes 11 are so placed in the coöperating flap as to come into the proper position to receive the respective buttons with which they coöperate in holding the garment in position on the wearer.

An apron or shield 12, being substantially triangular in shape, is provided at its upper extremity with button-holes adapted to register with the buttons 10. This shield 12 is preferably made of a water-proof material, such as cravenetted cloth or a cloth similarly treated, but the use of rubber for such water-proofing is entirely eliminated. The lower enlarged end of the shield 12 is preferably provided intermediate its width with darts 13, which are so arranged that they take up the fullness at the edge thereof and make the shield lie closer to the wearer. The upper end of the garment is preferably tapered inwardly to conform to the waist of the wearer, as indicated at 14. Thus it will be seen that the garment, having once been adjusted to the desired size, it will be unnecessary to change the adjustment when either removing or replacing the garment.

While in the foregoing I have shown and described the preferred embodiment of my invention, I wish it to be understood that I may change the specific arrangements of parts without, in any way departing from the spirit and scope of my invention.

Having thus fully described my invention, what I claim is:

In combination with an undergarment, comprising a limb receiving portion having a slit on its inner side, flaps formed on the

side of the limb receiving portion at the upper extremity of the slit, a second limb receiving portion having a slit adjacent its upper end, flaps extending laterally from the upper extremities of the slits, buttons attached to the waist band of the garment, one of said buttons being positioned adjacent the end of the second mentioned flap, a button placed substantially in the center of the garment and a third button attached to the waist band of the garment substantially the same distance from the center button as the first mentioned button, the first men-

tioned flap having button-holes adapted to engage the button; a shield having button-holes at the upper extremity to engage the aforesaid button, and darts in the lower edge of said shield and adapted to cause said shield to more closely engage the person of the wearer. 15

In testimony whereof I affix my signature in presence of two witnesses. 20

AUSTIN VICKERS.
